[57] CLAIM

The ornamental design for a reel assembly, as shown and described.

DESCRIPTION

FIG. 1 is a left side, partial rear and partial top perspective view of a reel assembly showing my new invention; FIG. 2 is a right side, partial front and partial top perspective view thereof;

FIGS. 3 and 4 are respectively right and left elevational views thereof; and

FIGS. 5 and 6 are respectively front and rear elevational views thereof.

The broken line showing of cord and light bulb is for illustrative purposes only and forms no part of the claimed design.

FIG. 2

FIG. 1

FIG. 4

FIG. 3

FIG. 6

FIG. 5
